FURNACE

James McDonald, Dudley, England, assignor of
one-half to G. W. B. Electric Furnaces Limited,
Dudley, England

Application September 18, 1942, Serial No. 458,869
In Great Britain October 2, 1941

3 Claims. (Cl. 214—18)

This invention relates to the use of jiggling, vibrating or reciprocating trays to carry work through continuous furnaces. The word furnace is used in a wide sense to include heat treatment chambers whether used for heating, cooling or maintaining temperature and the invention is designed to provide improved furnaces of the kind to which the work is progressed on jiggling vibrating or reciprocating trays.

From one important aspect the work carrying tray is carried upon transverse supports which extend through the side walls of the furnace, the ends of the supports being preferably carried in turn by external longitudinally extending members suitably suspended or supported and transmitting or partaking of the movement of the tray.

Expansion and contraction of the tray caused by temperature changes can be allowed for by a slotted connection between tray and transverse support.

The above and other parts of the invention will be clearly understood from consideration of a typical furnace illustrated by the accompanying drawings, the parts for which a monopoly is desired being those set out in the claims. The particular form of furnace illustrated is intended to be capable of carrying out an annealing operation as a continuous process upon suitable small blanks or other articles.

In the diagrammatic drawings—

Fig. 1 is a side elevation showing the exterior of the furnace chamber.

Fig. 2 is a longitudinal sectional elevation of the same, showing also the feeding and discharge arrangements and the drive, and

Fig. 3 shows the furnace chamber in cross-section.

As illustrated the furnace is of recuperative type in which the work is fed from a vibrating hopper 1 and chute 2 onto an upper tray 3 and then back along a return tray 4. The recuperative chamber is indicated at 5 and the heating chamber at 6 with heating elements indicated at 7. The trays 3 and 4 are supported upon transverse shafts 8, these shafts (except the end ones 8a which are secured to the trays) being a sliding fit in the grooves formed by brackets 9 secured under the trays. The grooves permit of expansion of the trays under heat. The shafts 8 and 8a project outside the furnace and are located in longitudinal beams 10 and 11 which act as connecting rods. The beams are in turn supported by inclined links 12, 13 respectively which guide the beams through a small upward and forward motion represented by the arc through which the

end of the inclined link is moved by the action of (for example) the eccentric 14 and connecting rod 15. Alternatively the beams might be supported by inclined planes and rollers or other conventional and equivalent arrangements, and the links or other supports need not be of the same in number as the transverse shafts. When under heat, the relative position of the shafts 8 will not alter as they are located in the beams 10 and 11 which are outside the furnace and maintained in cold condition. The trays however, will expand longitudinally and remain in the dead level condition. On each shaft end sealing means, for instance a large diameter brass cupped washer 16, is fitted, with a spring 17 on the shaft end which maintains the constant pressure of the washer on the furnace casing. The cupped washer 16 can be heat insulated and is of such diameter that in any position of the stroke the enlarged hole in the furnace casing will be completely covered and therefore unnecessary heat losses or air infiltration will be eliminated. It will be appreciated that the possible arcuate movement of the beams 10 and 11 and of the cross shafts 8 is so relatively slight, that the openings in the furnace through which the shafts extend may be and preferably are circular in cross section and of a diameter to permit the limited movement of the shafts.

In the case of the recuperative furnace shown in which the work is progressed along an upper tray 3 and then back along a return tray 4, a convenient design is one in which the longitudinal beams 10 carrying the upper tray are suspended by links 12 from fixed pivots 18 above and the lower tray supported by links 13 from fixed pivots 19 below. As shown, the connecting rods 15 are directly attached to the lower beams 11 and the upper beams 12 are coupled to the lower beams by connecting links 20. The upper links 12 will then incline downwards and forwards, so that upward movement along the arc and the working stroke of the upper tray are towards the right as shown by Figs. 1 and 2. And the lower links 13 will incline upwards and backwards, so that upward movement along the arc and the working stroke of the lower tray are towards the left.

It will be noted that the trays 3 and 4 are shown of upwardly concave gradually curved form. It is found that this form enables articles of a great variety of shapes to be evenly progressed: and in particular in the manufacture of deep hollow cylindrical articles from sheets it provides a method of annealing blanks and cupped or cylindrical forms produced from the several stages of draw-

ing or pressing the blanks at their various stages of manufacture requiring annealing.

It will be clear that the invention is not intended to be limited in its wider aspects to the details of construction, but to include all such arrangements as embody the underlying ideas and come within the words of the claims.

I claim:

1. In a furnace of the kind referred to, the combination of a heat treatment chamber including side walls, a substantially horizontal work carrying tray, transverse members supporting the tray and extending through enlarged apertures in the side walls, external members outside each side of the chamber, a firm connection between the external members and the transverse members, one of the transverse members being firmly connected to the tray and longitudinally slotted connections for connecting the remaining transverse members to the tray, and means to impart jigging movement to the external members and thereby to the tray to progress the work along the tray.

2. In a furnace having side walls, upper and lower trays movable in said furnace, transverse members extending through the side walls and operatively connected to the trays for operating them, certain of the transverse members of each tray having a limited loose connection with the particular tray, upper and lower bars extending longitudinally of each side wall and connected respectively to the ends of the extended ends of the transverse members of the upper and lower trays, links for supporting said bars for movement relative to the furnace, a connection between the upper and lower bars adjacent each side wall of the furnace, and means for directly operating the lower side bar beyond each side to thereby operate the upper bars and the trays.
3. A construction as defined in claim 2, wherein the links supporting the upper and lower bars are relatively arranged to compel opposite feeding movements of the trays in operation of the bars.

JAMES McDONALD.
